UNITED STATES PATENT OFFICE.

BENJAMIN F. FREEBLE, OF JAMAICA, NEW YORK, ASSIGNOR TO SEWICKLEY ELECTRIC MANUFACTURING COMPANY, OF SEWICKLEY, PENNSYLVANIA, A CORPORATION OF DELAWARE.

DESIGN FOR AN ASH TRAY OR SIMILAR ARTICLE.

Application filed November 30, 1923. Serial No. 7,914. Term of patent 3½ years.

To all whom it may concern:

Be it known that I, BENJAMIN F. FREEBLE, a citizen of the United States, residing at Jamaica, in the county of Queens and State of New York, have invented a new, original, and ornamental Design for Ash Tray or Similar Article, of which the following is a specification, reference being had to the accompanying drawing, forming part thereof.

The figure is a view in perspective of an ash tray showing my new design.

I claim:

The ornamental design for an ash tray or similar article, as shown.

BENJAMIN F. FREEBLE.
